United States Patent Office

Des. 177,913
Patented June 5, 1956

177,913

COIN HOLDER

Michael Jankura, Stratford, Conn.

Application November 12, 1954, Serial No. 33,080

Term of patent 7 years

(Cl. D52—4)

Fig. 1.

Fig. 2.

Fig. 3.

Fig. 4.

Fig. 5. ⁸

Fig. 6.

Fig. 7.

Fig. 8.

In the drawing:

Fig. 1 is a perspective view of a coin holder showing my new design;

Fig. 2 is a front elevation;

Fig. 3 is a side elevation;

Fig. 4 is a rear elevation;

Fig. 5 is a top plan view;

Fig. 6 is a bottom plan view;

Fig. 7 is a vertical sectional view taken along the line 7—7 of Fig. 5; and

Fig. 8 is a vertical sectional view taken along the line 8—8 of Fig. 5.

I claim:

The ornamental design for a coin holder, substantially as shown.
